UNITED STATES PATENT OFFICE

MEHRAN KASPARIAN, OF JERSEY CITY, NEW JERSEY, ASSIGNOR, BY DIRECT AND MESNE ASSIGNMENTS, OF ONE-HALF TO JOHN FANARJIAN, OF JERSEY CITY, NEW JERSEY, AND ONE-HALF TO PAUL M. HAMMALIAN, JOHN M. HAMMALIAN, AND JACOB M. HAMMALIAN

FOLDABLE DESK

Application filed October 11, 1930. Serial No. 487,931.

This invention relates to improvements in foldable desks. One of the objects of this invention is to provide mechanism for causing the simultaneous movement of the horizontally-foldable and vertically-foldable members of desks or like pieces of furniture and particularly for desks having upper and lower compartments, one of which is provided with a vertically-swinging closure preferably adapted in extended position to provide a table top and the other of which is provided with horizontally-swinging doors arranged when in closed position to close the compartment and when in open position to extend at a right angle to the closed plane thereof and to support the table top.

Another object of my invention is to provide lever mechanism so arranged that the manual movement of a vertically-foldable table top into open or closed position will automatically cause a similar simultaneous opening or closing movement of a pair of doors or closures for a lower desk compartment and vice versa.

Another object of my invention is to provide a mechanism of the character specified which will be simple, economical to manufacture and not likely to get out of order.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:—

Fig. 1 is a front elevation of a desk embodying my invention;

Fig. 2 is a view, in perspective, showing the desk in closed position;

Fig. 3 is a section on the line 3—3 of Fig. 1, looking in the direction of the arrow, showing the foldable parts of the desk in extended position;

Fig. 4 is a section similar to Fig. 3, showing the foldable parts of the desk in folded position;

Fig. 5 is a section on the line 5—5 of Fig. 1, looking in the direction of the arrow, showing the foldable parts in extended position;

Fig. 6 is a section similar to Fig. 5, showing the foldable parts of the desk in folded position; and

Fig. 7 is a section on the line 7—7 of Fig. 6, looking in the direction of the arrow.

Referring now to these drawings, which illustrate a preferred embodiment, my invention comprises the application to foldable desks of mechanism for causing vertically-foldable and horizontally-foldable members thereof to be moved simultaneously upon the manual actuation of one of such members. By my invention, I cause the simultaneous movement of the horizontally-swinging doors to open and close the lower compartment of such desks upon the manual movement or actuation of a vertical closure for the upper compartment which preferably comprises a table top and is supported when in extended position upon horizontally-swinging doors of the lower compartment. I will now describe a desk embodying such foldable members and having applied thereto lever mechanism of my invention which is adapted to cause simultaneous folding of such vertical and horizontally-swinging closure members.

In the preferred form of my invention, a desk 1 is composed of a body portion of elongated shallow conformation having an upper body section 2 and a lower body section 3. The upper body section 2, as illustrated, is provided with the usual pigeon-hole shelves and partitions 2', 2" and has a foldable table top 4 pivoted or hinged at 5 to a horizontal dividing partition 6 and adapted to fold or swing vertically so as to open or close the upper compartment or section 2. The lower section 3 is provided with doors 7, hinged to the side frame members 1" by means of hinges 8 and adapted to swing in a horizontal plane or at right angles to the plane of movement of the foldable table top for the upper section 4. As illustrated, said doors 7 are provided with casings 9 having filing compartments 10 and drawers 11.

In the embodiment of my invention illustrated, each of the horizontally-swinging members 10 which, in the embodiment of my invention shown, comprises the doors 7 combined with the casings 9 is provided at a 5 suitable position intermediate the hinged edge and outer edge thereof with a vertically-extending fixed peg or pin 12 engageable by a horizontally-swinging door-moving arm 13 pivoted in pivot-brackets 14' mounted within the lower compartment on the side of the casing. As shown, each arm 13 has a 10 travelling connection with the door and, as shown, is provided with a slot 13' fitting over and engaging the pin 12 so that upon 15 movement of the said pivoted arm 13 about its pivot, the element or door to which the peg 12 is connected will be caused to move or swing horizontally on its hinges 8, the peg or pin during such movement will travel in 20 the slot 13' and it will be seen that such pivotal movement in opposite directions of the arm 13 will enable the swinging of the door 7 about the hinges 8 into open and closed 25 positions respectively. In the embodiment of my invention shown, I provide means operable upon the manual vertical movement of the writing top closure for the top section of the cabinet or desk body to actuate 30 the lever 13 into open and closed positions respectively. As illustrated, the door-moving lever arm 13 is connected with a crank arm 15 formed integrally with said door-moving arm 13 and extending horizontally 35 within the upper casing, said crank arm also preferably being formed integrally with an intermediate pivot portion 14 which extends vertically between the two compartments. Said crank arm 15 is, as shown, movable pivotally by mechanism connected with and operable by the vertically-movable or foldable 40 closure member.

In the preferred embodiment of my invention shown, the crank member 15 is movable 45 to swing the crank pivot 14 and door-moving arm 13 by providing a travelling connection between said crank-arm and operating-mechanism connected with the table top. As illustrated, I provide a crank-operating element 50 movable in a single horizontal plane and adapted in such movement to travel in a slot 15' in the arm 15 and during such travelling movement to swing said integrally-formed crank arm 15, pivot portion 14, and door-moving arm 13. As shown, I provide a 55 horizontally-reciprocable sliding bracket 16 guided to move in a single horizontal plane by means of a strap 17 and carrying on its upper surface a pin 16' adapted to engage 60 and travel in the said slot 15'. Said bracket is reciprocated by a connecting link 18 having a pivotal connection at 18' at one end with said bracket and at the other end having a pivotal connection 18' with a pivot 65 bracket 4' on the table top. The bracket 16

in the form shown has a guiding connection with the strap or track 17 by providing integrally with said bracket a loop 16' which fits over said strap or track and travels thereon. The parts are duplicated at opposite sides 70 of the desk so as to operate two doors, as shown.

In operation, a vertical movement of the table top either in closing and opening will move the link levers 18 to reciprocate the 75 bracket 16 along the strap or track 17 in a rectilinear line, said bracket 16, having its pin 16' engaging in the slot 15' of the arm 15, will, during such reciprocating movement, cause a rocking of the crank-arm and simultaneously therewith will rock the door-moving lever arm 13 which, because of its travelling connection by means of the slot 13' and pin 12, will swing the door and casing about its vertical hinge axis and these movements 80 of the said doors and table top are preferably so co-related through the mechanism that the doors will be opened and positioned beneath the table top when the same is moved into its full-open extended position and conversely, the doors will be moved into completely closed position just prior to the closing of the vertically-swinging table top. 85

Having described my invention, I claim:—

1. A foldable desk composed of upper and lower body sections, said upper body section having a vertically-swinging hinged closure member comprising, when extended, a writing table top and the lower body section being provided with horizontally-swinging 100 doors, lever mechanism connecting said doors and table top and arranged upon vertical movement of the table top to swing the doors horizontally into folded position to close the lower compartment and into open position to 105 support the table top, said lever mechanism comprising door-moving members pivotally mounted at the sides of the casing and having an operative connection with said doors, a crank arm operable to move said door-moving members and extending into the upper compartment, and lever mechanism having at one end a pivotal connection with the table top and at the other end having an operative connection with said crank arm. 110

2. A foldable desk composed of upper and lower body sections, said upper body section having a vertically-swinging hinged closure member comprising, when extended, a writing table top and the lower body section being provided with horizontally-swinging doors, lever mechanism connecting said doors and table top and arranged upon vertical movement of the table top to swing the doors horizontally into folded position to close the lower compartment and into open position to support the table top, said lever mechanism comprising horizontally-movable door-moving members pivotally mounted at the sides of the casing and having a travelling con- 125

nection with said doors, a crank arm operable to move said door-moving members and extending into the upper compartment, and crank-operating mechanism having at one end a pivotal connection with the table top and at the other end having a travelling connection with said crank arm.

3. A foldable desk composed of upper and lower body sections, said upper body section having a vertically-swinging hinged closure member comprising, when extended, a writing table top and the lower body section being provided with horizontally-swinging doors, lever mechanism connecting said doors and table top and arranged upon vertical movement of the table top to swing the doors horizontally into folded position to close the lower compartment and into open position to support the table top, said lever mechanism comprising horizontally-movable door-moving members pivotally mounted at the sides of the casing and having a slot and pin connection with said doors, a crank arm operable to move said door-moving members and extending into the upper compartment, and crank-operating mechanism having at one end a pivotal connection with the table top and at the other end having a slot and pin connection with said crank arm.

30 4. A foldable desk composed of upper and lower body sections, said upper body section having a vertically-swinging hinged closure member comprising, when extended, a writing table top and the lower body section being provided with horizontally-swinging doors, lever mechanism connecting said doors and table top and arranged upon vertical movement of the table top to swing the doors horizontally into folded position to close the lower compartment and into open position to support the table top, said lever mechanism comprising horizontally-movable door-moving members pivotally mounted at the sides of the casing and having an operative connection with said doors, a crank arm operable to move said door-moving member and extending into the upper compartment, crank-operating mechanism comprising a reciprocal bracket guided to move in a rectilinear line and having an operative connection with said crank arm, and a link having a pivotal connection at one end with said reciprocal bracket and at the other end having a pivotal connection with said table top.

55 5. A foldable desk composed of upper and lower body sections, said upper body section having a vertically-swinging hinged closure member comprising, when extended, a writing table top and the lower body section being provided with horizontally-swinging doors, lever mechanism connecting said doors and table top and arranged upon vertical movement of the table top to swing the doors horizontally into folded position to close the lower compartment and into open position

to support the table top, said lever mechanism comprising horizontally-movable door-moving members pivotally mounted at the sides of the casing and having a slot and pin connection with said doors, a crank arm operable to move said door-moving member and extending into the upper compartment, crank-operating mechanism comprising a reciprocal bracket guided to move in a rectilinear line and having a slot and pin connection with said crank arm, and a link having a pivotal connection at one end with said reciprocal bracket and at the other end having a pivotal connection with said table top.

In witness whereof, I have signed my name to the foregoing specification.

MEHRAN KASPARIAN.
